T. W. PRITCHARD.
PROCESS OF PRODUCING PURE TURPENTINE.
APPLICATION FILED SEPT. 3, 1912.

1,110,819.

Patented Sept. 15, 1914.

UNITED STATES PATENT OFFICE.

THOMAS WILLIAMS PRITCHARD, OF WILMINGTON, NORTH CAROLINA.

PROCESS OF PRODUCING PURE TURPENTINE.

1,110,819.

Specification of Letters Patent. Patented Sept. 15, 1914.

Application filed September 3, 1912. Serial No. 718,435.

To all whom it may concern:

Be it known that I, THOMAS W. PRITCHARD, a citizen of the United States, residing at Wilmington, in the county of New Hanover, State of North Carolina, have invented certain new and useful Improvements in Processes of Producing Pure Turpentine, of which the following is a description, reference being had to the accompanying drawings, forming a part hereof.

My invention relates to a process of refining turpentine, particularly that produced from treating the resinous wood by distillation, either destructive or otherwise, and has for its object the elimination of objectionable matter commonly found to be present in turpentine so produced by which its market value is lessened as compared with turpentine produced from the sap drawn from the tree by tapping.

In the production of turpentine from the wood itself by the application of heat either directly to the wood as by a bath of heated material or in the ordinary process of distillation either destructive or otherwise by the application of heat to a retort in which the wood is contained, it is found that more or less pine oil of somewhat greater viscosity than the turpentine is mixed with the turpentine and cannot be eliminated by redistillation. It is also found that almost always turpentine so produced from wood is characterized by odors which are more or less offensive and distinguish it on the market from the turpentine produced from the sap of the pine. These offensive odors are due either to aldehydes, which are more highly volatile than the turpentine, or to empyreumatic oils driven off from the wood by using a degree of heat more or less higher than that required to drive off the turpentine, or may be due to the presence of both aldehydes and empyreumatic oils.

It is the object of my present invention to produce a process by which the turpentine produced from wood may be freed from pine oil and freed from objectionable odor, and with this object in view my invention consists in the process hereinafter described and claimed.

Referring to the drawings Figure 1 is an elevation partly in section of an apparatus adapted to be used to carry out my process; and, Fig. 2 is a cross sectional view on line 55 *a—a* of Fig. 1.

In the drawings, which are to be understood as illustrative merely and not intended to limit the invention to the use of the apparatus shown, or any particular construction or arrangement of apparatus, 1 is a tank or retort adapted to contain the turpentine to be treated. Within this tank is preferably arranged a heating coil 2. In the tank near its bottom is arranged an air pipe 3, provided with numerous perforations, the pipe 65 extending across the tank and communicating at its ends with vertical air inlet pipes 4 open at their upper ends. A draw off pipe 5 leads from the bottom of the tank. In the top of the tank is an opening for the escape 70 of the vapors hereinafter described, which opening is covered on the interior of the tank by an inverted conical shield 6 having an opening 7 at its apex.

A branch pipe 10 controlled by a valve as shown leads from the steam or hot water pipe down outside the tank nearly to the level of its bottom, the steam or hot water pipe 11 being in communication with the heating coil 2 from the other end of which 80 leads outlet pipe 14. Surrounding the tank and extending considerably above half its height is an outer tank or bath 12 between which and the tank 1 the branch steam or hot water pipe extends, the vertical air inlet 85 pipes 4 being also between the tank 1 and the tank 12. Outlet 13 leads from the tank 12.

In the top of the tank 1 is an inlet opening 8 by which the turpentine to be treated may be introduced into the tank. Over the opening for the escape of the vaporized turpentine is a hood 9, from which delivery pipe 15 leads to a worm 17 in a tank 16 having overflow 18. From the lower end of the worm 17 leads pipe 19 with which one end of a transparent tube 20 is connected, the other end of the transparent tube being connected to a pipe leading to a tank 23 at a point near its top, this pipe having therein a valve 21 and having a valved 100 branch pipe 22 leading from it at a point between the transparent tube and the valve 21. Within the tank 23 opposite the end of the pipe into which the transparent pipe 20 leads is a baffle plate 24.

Leading from the bottom of the tank 23 is a drawoff pipe 26. From the tank near its upper end leads a pipe 27, suitable baffle plates 25 being arranged within the tank opposite the inner end of this pipe. The 110

outer end of this pipe 27 is connected with an injector or jet pump having inlet pipe 29 leading from any suitable water supply and having discharge pipe 30.

5 A gage class 31 on one side of tank 23 serves to show the level of the liquid in it. In its top the tank 23 is provided with a manhole 32 of usual construction.

In operation the tank 1 is partly filled 10 with the turpentine to be treated and the bath 12 is filled with hot water through the branch pipe 10 if the pipe 11 is used to supply hot water, or the bath may be otherwise filled with water and the water heated by 15 steam from branch pipe 10 if the pipe 11 is supplied with steam. Hot water or steam, as the case may be, is supplied to the heating coil by the pipe 11. If steam is used it should be wet steam, that is steam at a 20 temperature not much above 212 degrees F., the purpose of the heat supplied by the water in the tank 12 and the steam or water in the heating coil 2 being to warm the turpentine to be treated to about 212 degrees F. 25 and maintain it at this temperature without heating it to a temperature at which it would boil, or be vaporized by heat and be distilled over.

On starting the injector or jet pump 28 a 30 partial vacuum will be created in the tank 23, the worm 17, delivery pipe 15 and tank 1 and air will enter through the vertical pipes 4 and perforated pipes 3 to relieve this partial vacuum, the air so entering being heated 35 in the vertical pipes 4 by the hot water in the tank 12 to a temperature not exceeding the temperature of the water which as above stated is not above 212° F., and being discharged through the perforations in the 40 pipes 3 will bubble up through the turpentine in the tank. A current of warm air will thus be established, the air being drawn through the turpentine not forced into it. The turpentine being warmed is sufficiently 45 lightened to be carried over by this current of warm air while the pine oil having greater vapor tension than the turpentine will not be carried over but will be left in the tank 1, and the vapor thus formed will 50 pass out through the hood 9 and delivery pipe 15 into the worm 17 where it will condense and flow through pipes 19 and 20 into tank 23. The aldehydes carrying objectionable odors if present will probably not con-

dense and if they do not they will pass off 55 through the injector jet pump 28. As they are more volatile than the turpentine they will, if condensable, come through the worm at the beginning of the run and may be drawn off through the branch pipe 22. The 60 empyreumatic oils carrying objectionable odors being more viscous than the turpentine will remain in tank 1 with the pine oil. The shield 6 prevents any of the pine oil which may be carried up by the air currents from 65 being carried into the delivery pipe 15. By thus drawing the warm air in minute streams or bubbles through the warm turpentine more or less oxidation of the aldehydes takes place. As a result of the operation of the process as thus described a pure 70 turpentine is produced freed from pine oil and freed from objectionable odor, identical in appearance, in odor and in all other respects with the turpentine produced from 75 sap.

Having thus described my invention what I claim is:

1. The herein described process of producing pure turpentine by distillation of 80 turpentine containing impurities which consists in drawing through it air warmed to a temperature not substantially above 212° F. and condensing the vapor drawn off with the air.

2. The herein described process of producing pure turpentine by distillation of turpentine containing impurities which consists in warming the impure turpentine to a 85 temperature not substantially above 212° F. drawing air through it and condensing the vapor carried off with the air.

3. The herein described process of producing pure turpentine by distillation of turpentine containing impurities which consists in warming the impure turpentine to a 90 temperature not substantially above 212° F., drawing through it air heated to a temperature not substantially above 212° F., and condensing the vapors carried off with the 95 air.

This specification signed and witnessed this 30th day of August, A. D. 1912.

THOMAS WILLIAMS PRITCHARD.
